BABY NURSER

Ludwig Alvine Zohe, Syracuse, N. Y.

Application February 27, 1934, Serial No. 713,141
Renewed February 9, 1937

2 Claims. (Cl. 128—252)

This invention relates to baby nursers, and has for its object a nipple having an outlet which is normally closed and opened by the collapsing of the nipple, as when the baby bites the nipple, or in other words, a nipple which requires the baby to use its jaws to collapse the nipple in order to draw the liquid food out of the container.

It further has for its object, a nipple with an outlet orifice which is normally closed but which is opened by the collapsing action of the nipple in any radial direction the collapsing force is applied.

It further has for its object, a nipple having such an orifice which consists of slits radiating from a common center in different directions, and at least three different directions.

It further has for its object, a baby nuser including a collapsible nipple having substantially a solid base portion and a collapsible liquid food container, or bag, detachably mounted on the solid base portion to form an air tight joint.

It further has for its object, a nipple having a normally closed outlet orifice opened by the collapsing action of the nipple, and means as, for instance, a check valve at the inner end of the nipple which permits the food to be drawn through the nipple by the sucking action of the baby, or passed into the nipple by squeezing the collapsible container to feed babies that can not suck, because of an affliction as a cleft palate, hair lip etc., but which means prevents air from passing from the nipple back into the container for the food, as when the baby collapses the nipple by closing his jaws, and at the same time blows or gulps air.

It further has for its object, means carried by the nipple for preventing folding of the collapsible bag, or food container, to such an extent that it closes the inlet of the nipple.

The invention also has for its object, a nipple having means for attaching a collapsible bag thereto, and a breast portion, and also such a nipple with a breast portion having means for gripping an outside solid container and holding it rigid with the breast portion.

Other objects will appear throughout the specification.

The invention consists in the novel features and in the combinations and constructions hereinafter set forth and claimed.

In describing this invention, reference is had to the accompanying drawings in which like

characters designate corresponding parts in all the views.

Figure 1 is a plan view of this baby nuser showing the nipple as embodying a breast portion.

Figure 2 is a longitudinal, sectional view of the nipple and breast portion with a collapsible bag, the bag being shown as nearly filled with milk, or other food.

Figure 3 is a view, similar to Figure 1, of a nipple unprovided with the breast portion.

Figure 4 is a view, similar to Figure 2, showing a nuser without a breast portion, the container being shown as empty and collapsed.

Figure 5 is a cross sectional view on line 5—5, 15 Figure 2.

Figure 6 is a longitudinal, sectional view of a nuser including a nipple with a breast portion, an outer solid container, and an inner collapsible container.

Figure 7 is a sectional view on line 7—7, Figure 6.

Figure 8 is a fragmentary, sectional view, similar to Figure 4, with a nipple unprovided with a plug at its inlet end, or a check valve at its inlet end.

Figure 9 is an end view looking down on the collapsible container.

1 designates the nipple, and 2 the breast portion, the nipple having a comparatively solid base 3 located within the breast portion 2.

4 is a collapsible container for liquid food, this being of collapsible, more or less, elastic material, as of pure or latex rubber and hence, is capable of expanding and contracting at its upper open end over an annular shoulder 5 on the base 3 of the nipple. As here shown, the container 4 is provided with a ring or bead 6 at its upper end, which acts snap band fashion to contract the open end of the container around the neck of the nipple, and over the shoulder 5.

In order to facilitate the removal and replacing of the container on the nipple, the container is provided at its upper end with a flange, or flanges, here shown as tabs 7.

8 designates the outlet orifice of the nipple, this being normally closed, although it is shown as open for the purpose of locating it. This orifice is shown as formed by radially extending slits, here shown as three in number intersecting in a common center at 9 and extending radially in different directions, the slits here shown being in the general form of a Y. Owing to the formation of the orifice 8, it is normally closed, and is opened by the collapsing of the nipple under

the influence of the jaws of the baby, when nursing. Owing to the Y, or similar formation, it will open when collapsed regardless of in what radial direction the collapsing force is applied. 5 That is, the orifice will open in any position the baby holds the nipple in its mouth.

Preferably, in order to prevent the passage of air from the nipple into the container, as when the baby is biting on the nipple and blows or 10 gulps air, the nipple is provided with a check valve 10 near its entrance end. This is here shown as a flap valve composed of a thin piece of rubber mounted on the end of a plug 11 extending into the inner end of the nipple, and 15 formed with a passage through which the milk, or food, flows.

In order to prevent folding of the collapsible container 4, to such an extent that it would lap over the entrance end of the nipple and hence 20 prevent the outflow of food, stiffening means is provided, and that here shown is a comparatively rigid straight member 12 associated with the nipple, and here illustrated as projecting from the plug 11. The plug 11, with the stiffening strip 25 12, is here shown as a tube split at 13 and having a lengthwise portion, or half, removed below the plug.

In Figures 3 and 4, the nipple is shown as unprovided with the breast portion, and in Figure 8 30 the nipple is shown as unprovided with a check valve 10, and also unprovided with the plug 11. The nipple, shown in Figure 8, is, with the exception of the outlet orifice, the usual nipple, but 35 in addition is provided with a comparatively stiff base portion or annular flange 5.

In Figure 6, the nipple, with a collapsible container or bag, is shown as housed in an outer stiff shield, or container 16, this being usually a glass bottle, and the breast portion 20, of the nipple 40 100, is provided with means for interlocking with the upper open end of the bottle 16, and with a suction means for engaging the periphery of the bottle, and as here shown, the bead 40, corresponding to the bead 14 (Figure 2), is provided 45 with an internal groove 41 facing the periphery of the bottle and preferable, this groove is divided up into arcuate sections by partitions 17, here shown as four in number, the edges of the partitions pressing against the bottle. The bottle 16 50 is provided with an external annular flange 18 at its open end, under which the bead 40 hooks. The groove or sections 41 are for a suction cup which causes the breast portion to adhere to the glass bottle.

55 The breast portion is provided with a suitable ventilating hole 19 to permit the air to enter the outer container for the purpose of collapsing the inner container 4 as the food feeds outwardly

therefrom, so that the food is subject to the outer atmospheric pressure through the collapsible bag, and is not contaminated by coming in contact with the air of the room.

In operation, the container 4 is filled, or partly 5 filled, with milk, or other liquid food, and the nipple 1 coupled in air tight relation thereto by reason of the contractile upper open end of the bag over the shoulder 5 of the margin. If partially filled, air in the collapsible container is first 10 expelled by the nurse squeezing the collapsible bag until the air is exhausted. In nursing, the baby must bite the nipple to open the orifice 8 and suck the food out through the nipple, and as before stated, if the baby gulps wind while 15 holding the nipple collapsed, air can not pass back from the nipple into the container 4 so that at no time is there any appreciable amount of air in the container, and the container collapses as the food is drawn therefrom. The baby can 20 be nursed, or assisted in nursing, by squeezing the collapsible bag. Also, because of the collapsible bag, or container, the baby may manipulate the collapsible container in much the same manner that a baby manipulates the mother's breast 25 in natural nursing. When the container is used without an outer container or bottle 16, the stiffening member 12 holds the collapsible sack from bending to such an extent as to close the inlet end of the nipple. 30

What I claim is:

1. A baby nurser comprising a nipple having an inlet at its inner end and an outlet at its outer end, and an automatically collapsible container, the nipple having a plug portion extending into 35 and snugly fitting the mouth of the container, whereby the container is attached to the plug portion, and the plug portion extends partly into the container, and a projection attached to the nipple and extending therefrom lengthwise of the 40 container within the same for preventing the container from folding over the inlet of the nipple.

2. A baby nurser comprising a nipple having an inlet at its inner end and an outlet at its outer end, and an automatically collapsible container, 45 the nipple having a plug portion extending into and snugly fitting the mouth of the container, whereby the container is attached to the plug portion, and the plug portion extends partly into the container, and a projection attached to the 50 nipple and extending therefrom lengthwise of the container within the same for preventing the container from folding over the inlet of the nipple, said projection comprising a tubular portion extending into the inner end of the nipple, the passage of the tubular portion forming the inlet for the nipple. 55
